UNITED STATES PATENT OFFICE.

CLIFFORD NORTON, OF SOUTH ORANGE, NEW JERSEY, ASSIGNOR TO GRAHAM & NORTON COMPANY, OF NEW YORK, N. Y., A CORPORATION OF DELAWARE.

ELECTRIC SWITCH

Application filed February 2, 1923. Serial No. 616,485.

To all whom it may concern:

Be it known that I, CLIFFORD NORTON, a citizen of the United States, and a resident of South Orange, in the county of Essex and

5 State of New Jersey, have invented certain new and useful Improvements in Electric Switches, of which the following is a specification.

My invention relates to electric switches 10 and more particularly to switches designed for use as interlock switches in connection with elevator door operating mechanisms and known in the art as electric interlock switches acting to prevent operation of the 15 elevator when the door is open by opening a control circuit and maintaining said circuit in open position until the door is closed.

The switch is however alike applicable in other situations or conditions where it is 20 desired to control the operation of the mechanism by controlling the condition of an electric circuit to either cut off the power circuit or to govern the condition of a mechanical lock for the mechanism.

25 One of the objects of my invention is to provide a simple and cheap construction affording a complete housing of insulating material for the contacting members of the switch as well as to secure in general, ease 30 of assembly and dis-assembly, together with accessibility of the parts.

A further object of my invention is to provide a simple and cheap construction of switch insuring the rupture of any arc following the opening of the circuit at the 35 switch contacts.

Another object of the invention is to produce a simple and cheap construction of the 40 mechanical elements of the switch whereby the circuit may be opened or closed by the action of a suitable operating member or plunger.

A further object of the invention is to 45 avoid the difficulty incident to the operation of some forms of switch where one contact element makes rubbing contact with the other element and in moving off said element is liable to transfer an abraded conducting material on to a non-conducting or insulating surface, thereby tending to impair the insulation of the two poles or members from 50 one another when the circuit is opened.

Other objects and advantages of my in-

vention will be apparent to those skilled in the art from the drawings and following 55 description.

In the accompanying drawings Fig. 1 is a general side elevation and partial section of a switch embodying my invention and applied to an elevator or other door, the operation of which is to be controlled.

Fig. 2 is a sectional side elevation on the line 2—2 of Fig. 1.

Fig. 3 is a top view of the device.

Fig. 4 is a cross-section on the line 4—4 65 Fig. 1.

Fig. 5 is a cross-section on the line 5—5 Fig. 1.

Fig. 6 is a perspective view of the two 70 sections of the block of insulating material which carries the contacting members and, by its construction, affords a complete housing of insulating material therefor.

1 indicates a base plate on which the parts 75 of the switch are mounted, said base plate, when the switch is employed in connection with an elevator door, being properly secured to brackets or arms 2 fastened to the door opening or frame 3 in an obvious and well-known manner.

4 4' indicate a pair of substantially parallel circuit closing members adapted to be moved into and out of contact with one another for the purpose of making and breaking the circuit. These circuit closing members are mounted respectively in and completely housed by a block of insulating material suitably fastened in position upon the base 1. Said block is a bipartite or sectional block the two members or elements of which, indicated respectively at 5 5', are shown in perspective, separated from one another, in Fig. 6, the switch contacts or circuit closing members and other parts being, in this figure, removed therefrom.

The meeting line of the sections, when the parts are assembled complete, is indicated at 6 in the various figures, being shown as a double line merely for the purpose of indicating a line of separation, although in practice the two elements or sections would be firmly engaged with one another on the line of division when assembled. Each section of the block consists preferably of some tough insulating material like bakelite or 105 some variation of the same constructed for

di-electric strength. Any material, however, which can be readily machined or molded into the shape shown might be used.

The meeting faces of the blocks are provided with recesses for the two contact elements 4 4' and are also so formed in their meeting faces as to afford a space for the operation of a reciprocating member or plunger 7 which works in guideways formed in the meeting faces of the blocks all as will be presently described. When forced into the space between the contacting surfaces of said switch elements, the plunger acts to separate them and cause a rupture of the circuit and maintain the circuit in open condition by forming a barrier of insulating material between them. Said plunger in the open position of the switch would be, in practice, raised or operated to substantially the position indicated in dotted lines Fig. 1. In this position it forms an effectual arc-rupturing or preventing shield for the circuit closing members 4 4', thus insuring the rupture of any arc that might follow the opening of the circuit. In order to act effectively in this way, the element 7 is so formed as to extend laterally to a considerable distance beyond the edges of the members 4 4', as shown in Figs. 3, 4 and 5. The end thereof located above the contacting ends of the elements 4, when the switch is opened, also aids in this operation.

It will further be seen that the plunger 7 is of sufficient length to separate the switch contact members 4 4' throughout their whole length. To accommodate the circuit closing members 4 4' and afford a space also for the working of the plunger 7, the opposed or meeting faces of the insulating block sections 5 5' are each provided with a groove or recess of the form indicated. The deeper or countersunk portion of the recess, the bottom of which is indicated at 8, affords a space for the mounting of the contact elements 4 or 4' while nearer the edges or meeting faces of the blocks the recess is widened out to not only provide a space for the working of the plunger 7 but also to provide guideways for the plunger by the ledges 9 and the sides of the widened space or groove. Each element 4 4' may be preferably pivotally mounted near the bottom of its recess upon a pin 10 extending from side to side of the block section through the countersunk portion of the groove or recess and each is given a bias toward the other for the purpose of closing the circuit by means of a suitable coiled or other spring 11, which is seated in a socket formed or countersunk in the bottom of the recess in which the contact members move.

This construction of the pair of insulating blocks and manner of mounting and guiding the parts therein affords great strength, simplicity and ease of manufacture and also

provides a practical complete enclosure of solid insulating material around the working parts of the switch members.

On the top of each block section and adjacent the upper end of the groove in the face of the block a suitable binding post 12 is mounted for attachment of flexible connections 13 leading down through the recesses to the back of the circuit closing members and electrically united therewith in any suitable way. Said binding posts 12 also serve for attachment of the leading-in wires 14 which enter through an opening 15 in the top of the casing. A free space is afforded by the casing above the insulating blocks, as shown, for facilitating the making of connections after the switch has been installed.

The complete encasing of the switch is effected by means of a cover plate 16, the edges of which extend over the sides of the block and engage the back or base plate 1. To complete the insulation of the parts and decrease the fire hazard, a lining 17 of insulating material is also employed, which rests upon a ledge provided around the edge or end of the block sections as shown. Any suitable means may be employed for securing the sections 5 5' with their recessed faces in meeting relation. The means shown consist of two sets of fastening bolts or screws 18 passing through the insulating blocks and entering the base plate. One pair serves also to hold the cover. Any means, however, may be employed that will fasten the two sections firmly together in the position indicated, in which, as will be seen, the block affords a complete, solid housing for the operating members of the switch.

In Fig. 1 the switch is shown in circuit closing condition. By raising the plunger or member 7 to the position indicated by the dotted line, the two members 4 4' will be forced apart at their contacting ends and be insulated from one another by the interposed mass of insulation of which the plunger 7 is composed. As will be seen, the plunger rubs against the contacting surfaces and aids in keeping the same clean. The contacts also will have a slight rubbing motion upon one another, thus aiding in this result. This rubbing action is due to the fact that the two contact elements are independently spring-actuated and that they will not move to exactly the same extent in the operation of opening and closing the circuit.

The upper ends of the contact elements 4 4' may be inclined inwardly to form inclined planes against which the upper edges of the plunger 7 engage with the effect of multiplying the movement of the elements in opening circuit, thereby insuring a rapid or quick break.

The plunger itself may be made of bakelite.

lite or other suitable insulating material.

When applied to an elevator door, the lower end of the plunger may be pivotally connected by a link 20 with the lever 21 of the door operating mechanism, said lever itself being pivoted to the bracket 22 extending from the side of the door opening and being also connected with the door itself in the usual way, so that when the door is opened by the operator, the lever 21, through the link 20, will raise the plunger 7 and open the control circuit of the elevator. The connection between the link 20 and the lever 21 is, as shown more particularly in Fig. 2, by means of a pin extending laterally through the lever 22 and adapted to rock therein, while a threaded end of the link passes through an extension of the pin and is secured to and longitudinally adjustable therein by means of suitable nuts engaging the threaded portion.

In the position of the parts shown, the door is closed and the control circuit being closed, the elevator may be operated in the usual way. The link 20 and the lever 21 may be connected by means, as indicated, which will permit the time of closing or breaking of the circuit to be adjusted for different positions of the door.

It will be seen that in my improved construction of switch, any arc that might follow the rupture of circuit will be a horizontal arc and owing to the fact that all the conducting portions of the switch members are below the location of the arc there will be no tendency of the arc to eat its way downward into the space between the contacts, the natural action of an arc being to rupture itself in an upward direction. Furthermore the immediate rupture of the arc is expedited by the interposition of the mass of insulating material composing the block or plunger 7 in the space above the point of contact where the arc would naturally form. Furthermore, the arc is prevented from eating its way downwardly by widening of the space between the contact arms as shown below the point where they make contact with one another to close the circuit. While, moreover, the plunger itself at all times interposes a solid mass of insulating material operating as a shield against arcing through the whole length of said contact members.

What I claim as my invention is:—

1. In an electric switch, a bipartite or sectional contact carrying block of insulating material having a face of each section recessed to form a space completely enclosed by insulating material when the sections are held in meeting relation, two contacting members secured directly to said blocks respectively and working in said recess, said members having a bias tending to close the circuit and a circuit breaking member con-

sisting of a plunger of insulating material working in guideways formed in the recessed meeting faces of said blocks and adapted to be forced between the contacting ends of the circuit closing members to insulate the contacts from one another.

2. In an electric switch, a sectional block of insulating material carrying switch contacts secured respectively to said sections in recesses in opposed faces of the sections and combined with means for holding said sections in meeting relation.

3. In an electric switch, a bipartite or sectional block of insulating material, the opposing or meeting faces of which are provided with countersunk grooves or recesses combined with circuit closing members mounted in the countersunk portions of said grooves and a circuit breaking member of insulating material working in guides formed by the wider portion of said grooves.

4. In an electric switch, a sectional or bipartite block of insulating material having recesses formed in the meeting faces of each section to provide guideways for the operating member of the switch working in said recesses, said faces being also countersunk at the bottom of said recesses to afford spaces for two switch contact members mounted respectively therein and adapted to make contact with one another in the space between the meeting faces.

5. In an electric switch, the combination of two complementary blocks of insulating material each provided with a countersunk recess in its opposed or meeting face, means for securing the blocks in meeting relation, pivoted circuit closing members mounted respectively on pintles extending transversely through the countersink, said members being adapted to contact with one another to close the circuit and a circuit breaking member consisting of a body of insulating material working in guideways formed in the portion of recess nearer the meeting face and adapted to force said circuit closing members apart.

6. In an electric switch, a bipartite or sectional contact carrying blocks of insulating material, said blocks having recesses in their opposed faces formed with guideways for the operating member of the switch and countersunk recesses at the bottom of the guiding recesses having mounted in them a pair of pivotal contact members normally engaged, coiled springs in sockets at the bottom of said countersunk recesses and engaging said contact members to force them together, and means for holding said blocks in meeting relation to provide by their recessed faces a complete housing of insulating material for said contact members.

7. In an electric switch, a bipartite or sectional block of insulating material the sections of which are formed respectively

- with recesses in their opposed or meeting faces, a plunger working in the space between the faces and in guideways formed by grooves or recesses in said opposed faces,
5. two pivoted contact members mounted respectively on pivots in countersunk portions of said recesses back of the guiding portion, connecting posts secured to the ends of said blocks near their meeting faces and flexible
10. connections leading from the same through the countersunk portion of the recesses and attached to said pivoted contact members respectively.
8. In an electric switch, a sectional contact
15. carrying block of insulating material having its sections formed to provide, when the sections are secured together, a recess having guideways for an operating member reciprocating on the meeting line of the sections and a narrower countersunk recess back of the guiding portion in which members of the switch contacting with one another may be respectively mounted with the operating member interposed between them.
9. In an electric switch, a block of insulating material consisting of two members each formed in one face with a contact carrying recess widened near the face of the member into a space for an operating member of the switch, and each provided around its end with a ledge for engagement by a sheet of insulating material extending beyond the block.
10. The combination of a reciprocating plunger of insulating material, a pair of normally closed switch contact members arranged in position to be separated and to open the circuit by the interposition of the plunger, a link pivotally connected to said plunger, an operating lever, a pin or stud adapted to rock in said lever and having a lateral extension and nuts engaging the threaded end of the link and disposed at opposite sides of said extension.
- Signed at New York, in the county of 45 New York and State of New York, this 1st day of February, A. D. 1923.
- CLIFFORD NORTON.
